UNITED STATES PATENT OFFICE.

HARRY ETHERIDGE, OF ZELIENOPLE, PENNSYLVANIA.

MEANS FOR FASTENING RAILWAY RAILS TO THEIR SUPPORTS.

Application filed February 3, 1926. Serial No. 85,719.

This application is, in part, a continuation of Letters Patent of the United States No. 1,572,131, granted to me on February 9th, 1926.

The object which I have in view is the provision of new and improved means for attaching the rails to their supports, such as individual rail supports, as specifically described in my said patent application, or to cross ties or supports. In general my improved fastening means permits the longitudinal movement of the rails due to their expansion or contraction without loosening the fastening means or impairing their efficiency.

For this purpose I provide a clamping member which engages the edge of the rail base and which is arranged to rotate to a limited degree so as not to interfere with the movement of the rail in expanding or contracting.

Preferably I provide resilient means for holding the clamping member in contact with the rail base.

In the preferred form of my invention, I employ a mat of compressible and resilient material upon which the rail rests, the mat extending sufficiently above the surface of the support so that the rail is held out of contact with the support.

While I have successfully made mats of rubber for this purpose, I have found that a mat of an asphaltum composition is most satisfactory. I prefer to use a plurality of mats, one of softer character, such as softer asphaltum seated in the bottom of the recess and a mat of harder character and therefore less compressible on top of the same and protruding sufficiently from the recess to assume the support of the rail and preventing the contact of the latter with the rail support.

In the accompanying drawings, wherein I illustrate the best embodiment of the principles of my invention now known to me, Fig. 1 is a plan view showing a rail fastened to a rail support; Fig. 2 is an enlarged view taken in section along the line II-II in Fig. 1; Fig. 3 is an enlarged broken side elevation of the rail and the fastening means, the material of the block or other rail support being omitted to better show the anchor of the fastening means; Fig. 4 is a plan view of one of the metal anchors which I embed in a concrete rail support to provide means for attaching the rails thereto; Fig. 5 is an en-

larged elevation of one of the rail clamps; Fig. 6 is a similar view of one of the split spring washers used in the rail attachment, and Fig. 7 is a sectional detail showing my improved rail mat in use.

Referring to the drawings, A represents a railway rail which is shown supported by an individual support B illustrated as of concrete. The upper surface of the support B is provided with a shallow sunken seat 3 in which is placed a resilient chair or mat D upon which the rail rests, the mat being of sufficient thickness to prevent the rail from contacting directly with the support B. The seat 3 extends longitudinally of the support B as shown.

I have employed with good results a soft rubber mat for this purpose, but I find that a composite mat, such as shown at D', D'' in Fig. 7 gives the best service. In Fig. 7 I illustrate the use of an under mat D' of softer material entirely contained within the seat 3 and an upper mat D'' of harder and less resilient material partially contained within the recess 3 but protruding upwardly therefrom sufficiently to support the rail from contact with the support.

I have employed asphaltum mats for this purpose, forming the mat of rag stock soaked in asphaltum preferably containing some rubber, say about ten per cent in volume. The upper and lower mats may be made of the same material but their relative hardness being obtained by different pressure under which they are formed, thus giving the under mat the consistency of soft rubber while the upper mat is hard enough to support the rail without material spreading.

If desired the seat 3 may be omitted and the mat D placed on the flat top surface of the support, but I prefer to provide the seat to insure the mat remaining in proper position.

G represents a transversely disposed anchor which, where the rail support is of concrete or similar material, is embedded in the support, one of said anchors being provided adjacent to each end of the support. These anchors are preferably malleable castings and comprise two vertically disposed cylindrical sockets 5 connected by an integral web 5^a. The web 5^a is entirely embedded in the material of the support B while the upper ends of the sockets 5 are flush with the top of the block at either side of the seat. The lower ends of the sockets 5 are closed and

exteriorly enlarged to provide a good anchorage in the material of the support B.

The bores of the sockets are threaded to receive the clamp bolts 6, the upper bores of the sockets being preferably unthreaded but of the full diameter of the bolt. H represents one of the clamps which fits down on top of the socket and through whose axial bore the bolt 6 extends. The head 7 of the 10 clamp is enlarged and preferably circular and has an arcuate or annular beveled under surface as at 8 to overlap and bear down on the base of the rail A as shown. The depending stem 9 of the clamp is arcuate or 15 cylindrical and bears against the edge of the rail base.

The top of the clamp is provided with a concentric circular seat 10 in which is mounted the split spring ring 11 against 20 which bears down the circular washer 12 overlapping the seat 10. When the bolt 6 is screwed down into the socket 5, the clamp H is forced down into resilient engagement with the rail so as to prevent the 25 latter from jumping from the rail support. However the rail is free to expand and contract the clamp H turning on its axis to permit the movement of the rail which it engages.

30 The bolt 6 does not contact with the bottom of the socket, and I prefer to place in the bottom of the socket a piece of waste 13 permeated with a suitable relatively stiff grease or other lubricant which will be 35 forced through the compression of the waste by the descent of the bolt to travel upwardly and lubricate the threaded engagement of the bolt and socket to prevent oxidation.

The provision of an elastic mat or cushion 40 between the rail and the rail support prevents pounding of the support and also preserves it. The resilient connection between the rail clamps and the support holds the rail securely to the support notwithstanding 45 the elastic cushion interposed between the rail and the support, thus preventing looseness between the rail and its support notwithstanding their cushion connection.

While the split spring ring 11 may be 50 omitted, if desired, I prefer to employ the same as it provides for the turning movement of the rail clamp without the possibility of looseness or tendency to rattle.

If desired the rails may rest directly on 55 the support, but I prefer to employ the resilient rail chairs or mats.

I have shown my invention applied to 60 concrete rail supports, but it will be understood to those skilled in the art that the principle of a clamp engaging the rail and mounted to permit at least a limited rotation may be applied to any known form of rail support without exceeding the limits of my invention.

65 It will be noted that the beveled surface

8 of the clamp H and the arcuate surface of the stem 9 effectually prevent a jumping movement of the rail relative to its support and also a lateral shifting movement.

What I desire to claim is:—

70 1. The combination with a support for a railway rail, of a clamp having an arcuate beveled surface adapted to fit down over the edge of the rail base, and means for securing the clamp to the support, said clamp being mounted so as to be free to rotate to allow for the movement of the rail due to expansion and contraction.

75 2. The combination with a support for a railway rail, of a clamp having an arcuate beveled head adapted to fit down on the base of the rail and an arcuate stem portion adapted to engage the edge of the rail base, said stem being provided with a cylindrical bore, and a cylindrical member extending down through the bore of said clamp and into the support, whereby said clamp is rotatably mounted on said member.

80 3. The combination with a support for a railway rail, of a clamp having an annular beveled head adapted to fit down on the base of the rail and a cylindrical stem portion adapted to engage the edge of the rail base, and a bolt extending down through said clamp and screwed into said support, said clamp being arranged to turn on said bolt to permit movement of the rail in expansion and contraction.

85 4. A fastener for securing a railway rail to its support comprising a clamp member having an axial bore and an annular beveled bearing surface adapted to fit down on the rail base, and a bolt extending down through said bore and into the support, said clamp being rotatable on said member to allow for the movement of the rails due to their expansion and contraction.

90 5. A fastener for securing a railway rail to its support comprising a clamp having an axial bore and an annular beveled bearing surface adapted to fit down on the rail base, a cylindrical stem adapted to engage the edge of the rail base, and an attaching bolt extending down through the bore into the support, said clamp being rotatable on said bolt to allow for movement of the rail due to expansion and contraction.

95 6. The combination of a fastener for securing a railway rail to its support, said fastener having a circular head provided with an annular beveled under surface adapted to engage the rail base from above, a cylindrical stem portion adapted to engage the edge of the rail base, a bolt extending down through said clamp and engaging the support, and a resilient member interposed between said clamp and the head of said bolt.

100 7. In a railway track structure, the combination with a rail support and a rail sup-

ported thereby, of a mat of resilient material interposed between the rail and the rail support, a clamp having a portion engaging the rail base, a bolt upon which said clamp is rotatably mounted so as to rotate to allow for the expansion and contraction of the rail and connecting said clamp to the

support and a spring interposed between the clamp and the bolt to take up the slack due to the compression of the mat.

Signed at Zelienople, Pa., this 29th day of January, 1926.

H. ETHERIDGE.
